(57) **CLAIM**

The ornamental design for a toothbrush handle, as shown and described.

DESCRIPTION

FIG. 1 is a perspective view as seen from the top, front and right side of a toothbrush handle showing my new design; FIG. 2 is a top plan view thereof; FIG. 3 is a right side elevational view thereof; FIG. 4 is a bottom plan view thereof; FIG. 5 is a left side elevational view thereof; and, FIG. 6 is a front elevational view thereof.

The broken lines showing a brush head are for illustrative purposes only and form no part of the claimed design.
